United States Patent Office

Des. 196,558
Patented Oct. 15, 1963

196,558

INFLATABLE PLAY PEN OR SIMILAR ARTICLE

Daniel S. J. Choy, 170 E. 77th St., and Gloria S. Vickery,
78 W. 12th St., both of New York, N.Y.

Filed Dec. 19, 1962, Ser. No. 72,897

Term of patent 14 years

(Cl. D5—5)

FIG. 1.

FIG. 2.

FIG. 3.

FIG. 4.

FIG. 2 is a side elevational view,

FIG. 3 is a perspective view, and

FIG. 4 is a sectional view on line 4—4 of FIG. 1.

We claim:

The ornamental design for an inflatable play pen or similar article, substantially as shown.
